UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

RAILWAY DRAFT-RIGGING.

1,398,674.

Specification of Letters Patent.

Patented Nov. 29, 1921.

Application filed May 24, 1920. Serial No. 383,651.

To all whom it may concern:

Be it known that I, ARGYLE CAMPBELL, a citizen of the United States, residing at Chicago, in the county of Cook and State of Illinois, have invented a certain new and useful Improvement in Railway Draft-Riggings, of which the following is a full, clear, concise, and exact description, reference being had to the accompanying drawings, forming a part of this specification.

This invention relates to improvements in railway draft riggings.

As is well known, the standard practice at the present time in the operation of European railway rolling stock, is to employ a hook and link connection between cars to effect the draft and separate bumpers to effect the cushioning action under buff. During the recent war, many cars of American manufacture employing the standardized automatic coupler were used in behalf of the American Expeditionary Forces with the result that the present European standard practice is slowly being changed to conform to that of the American practice. As will be evident, this change will require many years before completion and during such period of change, there will be many cars of the hook and link type of coupling and cars of the American type employing the automatic couplers. It is also evident that some means must be provided to permit the use of cars equipped in accordance with the American type with automatic couplers with both cars similarly equipped and cars equipped in accordance with European fashion in order that such American equipped cars may be kept in continuous service.

The object of my invention is to provide a draft rigging having a coupler so equipped that it is freely interchangeably usable with cars having automatic couplers of the American type or cars of the European type employing hook and link couplings.

Another object of the invention is to provide a draft rigging of relatively inexpensive application wherein provision is made for automatic coupling with other cars in accordance with the American practice and wherein the coupler shank is arranged to

directly actuate shock absorbing mechanism in both buff and draft so that the improved rigging may be equipped complete for cars for foreign use.

In the drawings forming a part of this specification, Figure 1 is a horizontal longitudinal sectional view of a portion of a railway car equipped with my improvements. In this figure, I have shown the end portion of an adjacent car equipped in accordance with the present European practice to more clearly illustrate the interchangeable use of my improvements with cars of such type as well as with cars equipped with automatic couplers of the American type. Fig. 2 is a longitudinal vertical sectional view corresponding substantially to the line 2—2 of Fig. 1. And Fig. 3 is an enlarged vertical transverse sectional view corresponding substantially to the line 3—3 of Fig. 1.

In said drawings, 10—10 denote channel-shaped center or draft sills of a railway car, the same being spaced apart any desired distance to accommodate the particular type of shock absorbing means used. In this connection, it is to be understood that there is no standard spacing at present provided for in European practice and hence the usual limitations imposed by the Master Car Builders' regulations in the United States need not be adhered to. My improved coupler is designated broadly by the reference A, the same extending outwardly beyond the end sill 11 of the car in accordance with standardized American practice. In order to adapt a car equipped with my improvements for use with foreign cars wherein the buffing shocks are absorbed by true buffers, the car will preferably be provided with two buffers indicated conventionally at 12—12, one at each side of the coupler. These buffers will project outwardly less than the distance to the end of the guard arm of the coupler and to such an extent that they will coöperate with buffers 13—13 of the type now commonly employed in European practice without danger of the hook 14 of such foreign cars striking against any part of my improved coupler.

In carrying out my invention, the coupler

A is provided with a coupler head conforming to standard practice, said head being provided with a guard arm 15, knuckle 16, knuckle pin 17, locking pin 18, and locking mechanism within the head, the details of which it is not deemed necessary to describe. The formation of the guard arm, knuckle and jaw will conform to the standards prescribed by the Master Car Builders' Association. The coupler head will also preferably be provided with a horn 19 co-operable with a buffering block 20 upon extreme inward movement of the coupler.

The shank 21 of the coupler is recessed so as to accommodate two transversely extending spring followers 22—22 and two corresponding keys 23—23. The keys are extended through slots 24—24 in the draft sills, the front key being movable rearwardly from normal position and the rear key movable forwardly from normal position. The shank of the coupler will preferably have a centrally extending vertical web 25 to act as a spacer for two twin arranged horizontally extending springs 26—26 and to maintain the springs in proper position, the coupler shank will have top, oppositely extended flanges 27—27 extending over the springs and curved downwardly at their outer ends as indicated at 28—28, so as to form, in effect, two receiving pockets. Over-compression of the springs is prevented and the keys are limited in their travel by leaving portions 29—29 of the sill webs in place as indicated in Fig. 1 and preferably the sills will be reinforced by plates 30 and 31 applied to the outer sides thereof as indicated in Fig. 1. As is clearly shown in Fig. 2, each spring follower 22 is provided with upper and lower horizontally extending flanges 32—32 straddling the corresponding key so as to hold the followers in proper position and in line with the centers of the springs 26.

In some cases it may be desirable to augment the capacity of the shock absorbing mechanism just described and to accomplish this I provide a simple and relatively inexpensive arrangement comprising a yoke 33 secured to the rear end of the coupler shank, a pair of followers 34—34, twin arranged rear set of springs 35—35 and ordinary front and rear stop lugs 36 and 37. The rear end of the coupler shank and the springs 26 are arranged to be supported by a detachable wide saddle plate 38 preferably bolted to the lower flanges of the sills and the yoke 33, followers 34 and springs 35 may be similarly supported by a detachable saddle plate 39. The keys 23 are held against accidental removal by any suitable means such as the cotters 40—40.

From the preceding description, it is evident that my improvements are adapted for use in conjunction with cars similarly

equipped or any car having a standardized automatic coupler. To permit the use of my improvements with cars equipped in accordance with the present foreign standard where hook and links are employed, I use the following construction: The knuckle pin 17 is of special construction and preferably is inserted from the bottom side of the coupler head and held against falling out by a nut 41 applied to the top of the pin. At its lower end, the knuckle pin is provided with an integral relatively heavy strong eye 42 to which one end of a chain 43 is adapted to be attached, said chain 43 having a hook 44 at its free end. As will be understood, said chain 43 and hook 44 will conform to the usual type of hook and chain indicated at 45 as now used in the standard European practice so that a draft connection may be made with a pair of chains and hooks as is now made where two cars of European standards are connected. To minimize bending and shearing strains on the coupler pin 17 when subject to tension from the chain 43, the coupler head is made with a slight modification, as compared with present American standards, by forming a heavy arcuate flange 46 at the lower end thereof with which is adapted to co-operate a corresponding annular flange 47 on the knuckle pin immediately above the eye 42. The flange or shoulder 46 obviously provides an abutment for the knuckle pin while at the same time permitting the latter to turn as needed.

It is thought that the use of my improvements will be fully understood from the preceding description considered in connection with the drawings without entering into a more detailed description of the shock absorbing means.

I am aware that various changes and modifications may be made in the details of construction without departing from the spirit of the invention and I contemplate all changes and modifications that come within the scope of the claims appended hereto.

I claim:

1. In a railway draft rigging interchangeably usable with automatic couplers of the Master Car Builders' type and hook and link couplings, the combination with a coupler having an M. C. B. automatic coupler head, including a pin for the knuckle; of a hook and link chain attached to said knuckle pin, whereby the coupler may be connected by said chain and hook with a car unprovided with an automatic coupler.

2. As an article of manufacture, a coupler interchangeably usable with automatic M. C. B. couplers and couplings of the hook and link type, said coupler having a coupler head including a jaw, knuckle, locking mechanism of M. C. B. type and a knuckle

pin, said pin having an eye at one end thereof, a chain and hook attached to said eye, the coupler head having a shoulder coöperable with the knuckle pin adjacent the eye thereof, said shoulder forming an abutment for the knuckle pin when under pull from the chain and hook.

In witness that I claim the foregoing I have hereunto subscribed my name this 4th day of May, 1920.

ARGYLE CAMPBELL.

Witnesses:

IRENE DRAKE,
WALTER GUNNISON.
